UNITED STATES PATENT OFFICE.

CARL W. WEISS, OF BROOKLYN, NEW YORK.

INTERNAL-COMBUSTION ENGINE.

No. 819,258.

Specification of Letters Patent.

Patented May 1, 1906.

Application filed March 6, 1902. Serial No. 96,878.

To all whom it may concern:

Be it known that I, CARL W. WEISS, a citizen of the United States, residing in the borough of Brooklyn, of the city of New York, 5 State of New York, have invented certain new and useful Improvements in Internal-Combustion Engines, of which the following is a specification, reference being had to the accompanying drawings, forming a part 10 hereof.

This invention relates to internal-combustion or explosive engines of a well-known character in which a trunk-piston reciprocates in the working cylinder and in which 15 the air which is mixed with a hydrocarbon vapor to form the explosive charge is compressed by the forward stroke of the piston within the inclosed crank-chamber and is conducted thence into the working cylinder 20 through a suitable port formed in the latter. In smaller engines of this type it is entirely practicable to cast the engine-frame, comprising the working cylinder and the crank-chamber, in one piece; but in larger engines 25 the casting for the frame is so large and heavy as to make it difficult to handle, and therefore to make it desirable, if possible, to form the frame in two parts, which are subsequently secured together. It is impractical 30, however, simply to divide the frame on any convenient line, because of the necessity of avoiding any joint in the cylinder through which the trunk-piston moves and of the further necessity of providing for the requisite 35 ports for the proper conduction of the air and the products of combustion.

It is the object of this invention, therefore, to provide for the construction of such an engine-frame in two parts, while meeting successfully the difficulties which present themselves, as above suggested.

The invention will be more fully described hereinafter with reference to the accompanying drawings, in which, for purposes of illustration and explanation, it is represented as embodied in a convenient and practicable form.

In the drawings, Figure 1 is a longitudinal vertical section, on a slightly irregular but 50 substantially central plane, of so much of an engine which embodies the present improvement as is necessary to enable the same to be understood. Fig. 2 is an end view of the cylinder portion of the engine-frame shown in Fig. 1, the cap over the air-channel being

omitted. Fig. 3 is an end view of the crank-chamber portion of the engine-frame shown in Fig. 1.

The cylinder portion A of the engine-frame may be of usual form and construction, except as hereinafter indicated. A water-jacket A' is provided for the cylinder portion and is of ordinary construction, except that it is wholly formed in or with the cylinder portion. The forward extension A² has such 65 length as is necessary for proper co-operation with the piston and is finished at a to fit closely within the seat provided therefor in the crank-chamber portion, as hereinafter described. It is also formed with a finished 70 face or shoulder a' to fit closely against the face of the crank-chamber portion. A port or channel a² is formed in the wall of the cylinder portion for the admission of the air from the crank-chamber into the working cylinder, one orifice of such port or channel being 75 located in the finished face or shoulder a', while the other opens into the working cylinder, as usual. For convenience this channel may be formed partly in a cap a⁵, which may 80 be formed separately. An air-port a³ for the admission of air to the crank-chamber is formed in the portion a of the cylinder extension A², and an exhaust-port a⁴ may be provided, as usual. 85

The crank-chamber portion B is formed substantially as usual, except that it is provided with a seat at b to receive with a close fit the portion a of the cylinder portion A. It is also provided with a finished face or 90 shoulder b' to fit closely against the corresponding face or shoulder a' of the cylinder portion, and with a port or channel b² to register with the corresponding port or channel a² of the cylinder portion, and also with a port b³ 95 to register with the corresponding port a³ of the cylinder portion. The cylinder portion A and the crank-chamber portion B may also be provided with lugs or ears, (marked a⁵ and b⁵, respectively,) through which may 100 pass bolts (not necessary to be shown) to securely unite the two portions. The plane of meeting of the cylinder portion and the crank-chamber portion is indicated by the vertical dotted line in Fig. 1. 105

The crank-chamber portion B may be supported, as usual, upon a subbase C, which may be provided with air-inlet ports c and c', the latter being formed in a web c². The division of the subbase by the web c², forming cham- 110

bers, and the provision of the inlets c and c' for the chambers, respectively, constitute a convenient muffle for the inrushing air.

The trunk-piston D may be formed as usual and connected by a pitman d with the crank-pin d' of the usual crank-disk d^2 .

The operation of the engine is substantially the same as usual. During the forward movement of the piston D the ports a^2 and a^4 , as well as ports a^3 , being covered, the air is compressed in the crank-chamber. As the piston approaches the limit of its forward movement the air under compression is admitted to the working cylinder through the port a^2 , driving out the dead gases of the previous explosion and filling the working cylinder with air which is mixed with the hydro-carbon vapor. During the return movement of the piston the mixture of air and vapor is compressed in the working cylinder, and as the piston approaches the limit of its rearward movement the port a^3 is uncovered by the piston and air is admitted to the crank-chamber to be compressed during the next forward movement of the piston. It will be observed that by the described construction there is no joint in the cylinder to interfere with or affect in any manner the proper action of the piston, while provision is made for

the proper delivery of the compressed air to the working cylinder, the proper discharge of the dead gases, and the proper introduction of a fresh supply of air into the crank-chamber.

I claim as my invention—

A frame for an explosive-engine comprising a base, an independent crank-chamber portion formed with an interior seat having an air-inlet port in said seat and a finished face, and an independent cylinder portion formed with a finished face to fit the finished face of the crank-chamber portion and having an extension fitting closely within said seat in the crank-chamber portion with a port arranged to be covered by the piston registering with the air-inlet port in said seat, said crank-chamber portion and said cylinder portion having other registering ports in their respective finished faces and an exhaust-port in the cylinder portion arranged to be covered by the piston, substantially as described.

This specification signed and witnessed this 27th day of February, A. D. 1902.
